[57] CLAIM

The ornamental design for a control panel for crane operator cab, as shown and described.

DESCRIPTION

FIG. 1 is a perspective view of the control panel for crane operator cab, embodying the new design;

FIG. 2 is a side elevational view of the control panel of FIG. 1;

FIG. 3 is an opposite side view of the control panel of FIG. 2;

FIG. 4 is a front view of the control panel of FIG. 1;

FIG. 5 is a rear view of the control panel of FIG. 1;

FIG. 6 is a top view of the control panel of FIG. 1; and,

FIG. 7 is a bottom view of the control panel of FIG. 1.

The broken line showing of buttons, switches and gauges is for illustrative purposes only and forms no part of the claimed design.
